TYPE-WRITING MACHINE.

No. 876,380.

Specification of Letters Patent.

Patented Jan. 14, 1908.

Application filed June 27, 1906. Serial No. 323,668.

To all whom it may concern:

Be it known that I, HERMAN P. MOORREES, citizen of the United States, and resident of Weehawken, in the county of Hudson 5 and State of New Jersey, have invented certain new and useful Improvements in Type-Writing Machines, of which the following is a specification.

This invention relates to improvements in 10 tabulating mechanism of typewriting machines and it consists of the features of construction, combinations and arrangements of parts which are hereinafter described and specified in the appended claims.

15 On the accompanying sheets of drawings on which like reference numerals designate like parts in the different views, Figure 1 is a side and sectional elevation of mechanism forming part of a Monarch typewriting 20 machine in which the invention is embodied; Fig. 2, a front elevation of a fragment of a frame including a portion of the right front post; Fig. 3, a rear and sectional elevation of said mechanism, some of the 25 parts being shown broken; Fig. 4, a side elevation, on an enlarged scale, of devices shown in Fig. 1 at the back and upper part of the machine, one of these being a denominational stop-device; Fig. 5, a rear elevation, 30 partly sectional, of this stop-device and certain other parts and fragments of parts of the machine; Fig. 6, a perspective of this stop device; Fig. 7, a plan thereof; and Fig. 8, a broken side elevation and vertical section of 35 parts in operation, these parts being shown in Fig. 4 in their normal positions.

Although the invention is shown as it appears when embodied in a Monarch typewriting machine, it is to be understood that 40 it may be applied to typewriting machines of various forms.

Parts of the Monarch machine which are well known and which are shown, or partly shown, in the drawings, are the frame of the 45 machine, the platen and platen carriage, the step-by-step feed mechanism, the column stop bar with column stops thereon, the tabulator key with the parts operative thereby to turn the column stop bar on its axis, and 50 the carriage release lever and rack lifting device also operative by the tabulator key.

The frame of the machine comprises a base 1, posts 2 and a top plate 3. On and near the rear of the top plate two standards 4 are

affixed and to these standards grooved guide 55 rails 5 and 6 are attached by means of screws 7 and 8, the length of these guide rails being about equal to the width of the top plate. The platen frame or carriage 9, in which the platen 10 is mounted, has formed on it at the 60 back of the carriage, grooved guides 11 and 12, and between the rail 5 and the guide 11 and between the rail 6 and the guide 12 are anti-friction balls 13 and 14 respectively.

The carriage and platen are supported by 65 the standards 4 to which the carriage is connected by means of the grooved rails and guides and the anti-friction balls described, the platen and platen-carriage being movable back and forth over the top plate of the 70 machine. On the inner face of each end of the platen frame or carriage an arm 15 is pivoted by a pin 16, these arms extending backward from their pivots between the guides 11 and 12, and to the rear ends of 75 these arms is attached a feed rack 17. Springs 18 bearing on the arms 15 tend to keep these arms and the feed rack in their normal positions as they are shown in Figs. 1 and 3 of the drawings. The rack 17, nor- 80 mally engages a feed pinion 19 which is mounted on a shaft 20, this shaft having a bearing in a block or standard 21 which is fast on the top plate of the machine, and on the shaft 20 and operatively connected there- 85 to in the usual manner is an escapement wheel 22. Feed dogs 23 and 24 which co-act with the escapement wheel are mounted on an arm 25 of a dog rocker, said arm extending upward from a rock shaft 26 which has 90 bearings in a bracket 27, this bracket being affixed to and extending downward from the top plate of the machine.

On the rock shaft 26 is a coil-spring 28 which tends to keep the arm 25 in the position in which it is shown in Fig. 1, the stepping dog 23 then being engaged with the escapement wheel. An arm 29 which is fast 95 on the rock shaft 26 and extends forward therefrom, is connected in the usual manner 100 by a link 30 with a universal bar (not shown), on which the key levers of the type bars and the spacing key act when they are depressed. The construction of the step-by-step feed mechanism just described is such that when 105 the spacing key or a type actuating key is depressed the arm 25 is rocked forward and when the key is released this arm is restored

to its normal position by the action of the spring 28, whereupon the carriage moves a letter space distance toward the left. The carriage is drawn toward the left, whenever the dog rocker is actuated as described, by the action of a spring drum 31 which is connected by a strap 32 with a stud 33 fixed to and projecting downward from the platen carriage near its right end.

10 Arms 34 are formed on the standards 4, these arms extending backward from the upper ends of the standards, and at the rear ends of the arms are bearings in which a column stop bar 35 is mounted, a column stop 15 or column stops 36 being secured on this bar by means which renders said stop or stops adjustable along the bar. The stop bar 35 extends through the right arm 34, and on the end of the bar near this arm is a crank arm 20 37 which is fast on the stop bar. A rod 38 is pivoted to the crank arm 37 and extends downward therefrom through the top plate into the base 1 of the frame. A collar 39 is fixed on the rod 38 below and near the top 25 plate and on this collar is a projection 40. A coil spring 41, which surrounds the rod 38, bears at its upper and lower ends respectively against the collar 39 and the part 42 of the base of the frame and tends to keep 30 the rod 38, arm 37 and the column stop bar and stops described, in the positions in which they are shown in Figs. 1 and 4. The rod 38 is pivoted at its lower end to a lever 43, whose fulcrum is a screw 44 which extends 35 through the lever into a projection 45 formed on the base of the frame, this lever having on it an ear 46 in which is a slot 47. A key lever 48 is pivoted by a pin 49 to a lug 50 which is fast on the base of the frame, 40 and on this lever is fixed a pin 51 which extends through the slot 47 in the lever 43. The key lever 48 is provided with a finger button or key 52 and normally rests near its front end against a pad 53.

45 A lever having arms 54 and 55 is pivoted by a screw 56 to a lug 57 formed on the under side of the top plate 3, the arm 54 of this lever extending under the projection 40 of the collar 39 and having on it a stop 58 50 which normally rests against the under side of the top plate. The left arm 55 (as viewed from the front of the machine) of this lever is pivoted to the lower end of a rack-lifting device 60 which extends upward from the 55 lever on opposite sides of the bearing 21 of the shaft 20, and has at its upper end horizontal portions 61 which rest normally under and near the feed rack 17.

The key lever 48, when the finger button 60 52 is depressed, operates as does the ordinary tabulator key lever of the Monarch machine to turn the stop bar on its axis so that the stop lug 62 of each column stop 36 is moved downward, while the carriage is at rest, into 65 the path of a co-operative stop which travels

with the carriage in its movement from side to side of the machine, the lever 48 being also operative, through the collar 39 and projection 40, on the lever 54—55 to raise the rack lifting device 60 and disengage the rack 17 from the feed pinion 19, thus releasing the carriage from the control of the step-by-step feed-mechanism. When the key lever 48 is released the parts operated thereby are restored to their normal positions by the action of gravity and of the restoring springs 18 and 41.

The tabulating mechanism which has heretofore been applied to the Monarch machine comprises a stop which is fast on the platen carriage, and which is movable thereby into contact with the stop lug 62 of a column stop 36, when the stop bar has been turned as described by means of the tabulator key 48.

The mechanism in which this invention is embodied comprises a stop device which is co-operative with each of the column stops 36, and which takes the place of and performs the function of the stop above mentioned, 90 which has heretofore been affixed to the carriage of the machine. The stop device herein shown also co-operates in a peculiar way with each of the column stops 36 to produce additional results as will herein- 95 after more clearly appear.

This device consists of a part or arm 63 having at one end an eye 64, and of a curved part or head 65 formed on the arm 63 and included between cylindrical surfaces 100 whose common axis is that of the eye 64. On the head 65, along its upper and front edge, is formed a series of notches having vertical faces as well as faces which lie in planes containing the axis of the eye 64, 105 the planes containing said vertical faces being perpendicular to the axis of the eye. The vertical faces of these notches constitute denominational stop-facets 66, 67, 68, 69, 70, 71, 72 and 73, the distance from one 110 of said stop-facets to the next being a letter space distance. Although eight of such denominational stop-facets are shown it should be understood that a different number may be provided if desired. A column 115 stop-facet 73' is also formed on the head of this device, its plane being parallel to the planes of the denominational stop-facets. Ribs 74, 75, 76, 77, 78, 79 and 80 are also formed on the head 65 of this stop device, 120 the left face of each rib, as the device is viewed from the front of the machine, being in the plane of one of the stop-facets, and the upper or front ends of these ribs being even with those faces of the aforesaid 125 notches which are in planes containing the axis of the eye 64. The upper surface 81 of the head 65 and the upper or convex edges of the ribs formed on the head are parts of a cylindrical surface whose axis 130

coincides with that of the eye 64, and the surface 82 and the bottoms of the grooves between said ribs, as well as the bottom of the groove 81' and the surface 74' next to the rib 74, are parts of a smaller cylindrical surface having the same axis. This stop device is mounted on a rock shaft 83 which has bearings in the standards 4, the shaft passing through the eye 64 of the stop device. This eye is confined between lugs 84 and 85 formed on a bracket 86 which is fast on the platen carriage and the shaft 83 extends through these lugs and is loose therein. In this shaft is a groove 87 which extends from end to end thereof, and in the arm 63 of the stop device is a spline 88 which fits in the groove 87 and by means of which the stop device is so engaged with the shaft that when the shaft is turned on its axis the stop device will be turned with it. This device is so mounted on the shaft that the stop-facets and the left faces of the ribs above mentioned are in planes which are at right angles to the axis of the platen, and 25 the device is movable by the carriage towards the sides of the machine along the shaft 83, the spline 88 being loose enough in the groove 87 to enable the stop device to be easily moved by the carriage.

30 To the lug 84 of the bracket 86 is attached a clutch member 89 which has ratchet clutch teeth thereon, this clutch member having a hollow hub which extends through the lug 84, loosely surrounding the shaft 83 and is made fast in the lug by means of a set screw 90. Another clutch member 91 is attached to the stem 63 of the stop device described, this member having ratchet teeth which are adapted to engage with the teeth of the other 40 member. A coil spring 92 surrounds the shaft 83, one end of this spring being in a recess in the lug 85 of the bracket 86. This spring presses against the right face (as viewed from the front of the machine) of the eye 64 of the stop device and tends to keep the members of the clutch in engagement with each other.

The arrangement of the rod 83, the stop-device mounted thereon, and the column 50 stops 36, is such that when the stops 36 are in their normal positions the lugs 62 of these stops are then further from the axis of the rod 83 than are the surface 82 and the bottoms of the grooves between the ribs on the 55 head 65 of said stop-device, and the lower front corners of these lugs are then nearer to said axis than is the cylindrical surface which contains the upper edges of said ribs, and the front ends of these lugs are then behind the 60 plane which contains the axis of the rod 83 and the lower and rear ends of said ribs, and above and in front of the plane which contains said axis and the rear edge of the surface 82, and that when the stops 36 are in 65 their operative positions the front edges of

the lugs 62 are nearer to the axis of the rod 83 than are the surface 82 and the bottoms of the grooves between said ribs.

On the end 93 of the shaft 83 is a crank arm 94 which is fast on the shaft and to which is pivoted a rod 95. This rod extends downward through the top plate and through the part 42 of the base of the frame, and fast on the rod between the top plate and the base is a block 96 having on it pivot pins or gudgeons 97. A coil spring 98, surrounding the rod 95 and bearing at its upper and lower ends respectively against the block 96 of the base of the machine, tends to keep the rod 95, the shaft 83 and the stop device described, 70 in the relative positions in which they are shown in Figs. 1, 3, 4 and 5 of the drawings. A hanger 99 is fastened to the top plate near its right edge and extends downward therefrom, and to this hanger at its lower end is 75 pivoted by a shouldered screw 100 a lever and an actuating device, the lever having arms 101 and 102 and the actuating device 103 being slotted and extending on both sides of the lever around their common pivot 80 axis and thence directly under the arm 101 of the lever to and past the front end of the lever. In the arm 101 of the lever is a screw 104 which is arranged to make contact with the upper edge of the device 103 when 85 this device and the lever are in the positions in which they are shown in Fig. 1. The arm 102 of this lever is forked at its rear end and extends on opposite sides of the block 96, the gudgeons 97 of this block passing through 90 slots 105 in the lever. This lever and the device 103 both extend through a slot 106 in a plate 107 which is attached to the front posts of the machine frame. A knob 108 is attached to or formed on the lever at its 95 front end, this knob being both a finger piece and a pointer; the pointer coöperating with a denominational scale on the plate 107. A finger piece 109 is formed on or attached to the front end of the actuating device 103, 100 the relations of the knob 108 and finger piece 109 being as they are shown in Fig. 1, when 105 the lever and the actuating device are in their normal positions. The denomination scale shown in Fig. 2 of the drawings and there 110 marked "JM.", "HT.", "10T", "T", "100", "10", "1", "1", is formed on the plate 107 and next to one edge and above the slot 106. An upright rod 110 is received in an opening 115 in and is guided by lugs 111 formed on or attached to the front and right post of the frame, the rod being movable up and down through these lugs. The rod is normally held in the position in which it is shown in Fig. 1 by a coil spring 112 which bears at its 120 lower end against the lower lug 111 and at its upper end against the collar 113 fast on the rod, the collar bearing against the upper lug 111 to limit the upward movement of the rod. On this rod below the lower lug 111 is 125 130

a collar 114 from which a pin 115 extends under the actuating device 103, this collar being fast on the rod. This rod is bent near its lower end so that it extends to the left of the associated corner post 2 and over the key lever 48, the part 116 of the rod being directly over and a short distance above the lever 48 when the lever and rod are in their normal positions.

10 When it is desired to use the tabulating mechanism described merely for the purpose of arresting the carriage at a desired columnar position, the key 52 is depressed and the stop bar or rock shaft 35 is thereby turned so 15 that the lugs 62 of the column stops 36 are brought into the path of the stop-facet 73' and the carriage is released from the escapement mechanism by the action of the rack lifting device on the feed rack 17, this device being raised by the downward pressure of 20 the projection 40 on the arm 54 of the lever 54-55. The carriage is then drawn to the left by the spring drum 31, the stop device on the shaft 83 being moved along this shaft by 25 the carriage until the stop-facet 73' contacts with the first column stop 36 and the eye 64 of the stop device mounted on the shaft 83 is forced against the tension of its spring 92 and into contact with the lug 85 of the 30 bracket 86, whereupon the carriage is arrested. The effect of moving the stop device against the tension of the spring 92 is to disengage the clutch members 89 and 91 which disengagement occurs when the carriage 35 is arrested by the tabulating mechanism and through the impact of the tabulating stops. Then, when the tabulator key 52 is released this key and the parts actuated thereby, including the column stops 36 40 and the carriage release mechanism are returned to their normal positions, so that the carriage is restored to the control of the step-by-step feed mechanism and the column stops are withdrawn from the path of the 45 stop-facet 73'. The coil spring 92 then forces the stop device along the shaft 83 to the left until the clutch member 91 is brought into contact and in engagement with the clutch member 89. When the key lever 48 50 is actuated as described by depressing the key 52 no angular movement is imparted to the stop device mounted on the shaft 83, the key lever 48 being movable from the part 116 of the rod 110 without affecting the position of this rod or that of the lever 101-102, or the position of any of the parts of the mechanism which connects this lever with the shaft 83. If, however, it is desired to arrest 55 the carriage at a denominational position the finger piece or key 109 of the actuating device 103 is grasped by the operator, his finger preferably being placed at the same time on the knob 108 of the lever 101-102, the front ends of the actuating device and 60 lever are raised until the pointer 108 is even

with the scale mark indicating the desired denominational position and then the key 109 is depressed to the lowest limit of its movement independently of the lever 101-102, so that the actuating device 103 is brought 70 into contact with the pin 115 on the collar 114 and the rod 110 is moved downward by the action of the device 103 on the pin 115 and the front end of the lever 48 is depressed by the part 116 of the rod 110. With 75 the upward movement of the front end of the lever 101-102 as described the block 96 on the rod 95 is forced downward by the rear end of the lever, and this rod acting through the crank arm 94 and shaft 83 on the denominational stop device turns this device angularly so that the proper denominational stop-facet shall be in alignment with the lugs 62 of the column stops 36 when the column stops shall have been turned to their operative positions. 80 85

As the denominational stop device is turned as described the sloping faces of the ratchet teeth on the clutch member 91 are moved backward with the stop device over the sloping faces of the ratchet teeth of the other clutch member and when the stop device reaches the end of the movement imparted to it by actuating the key lever as described the straight faces of the clutch member 91 engage with the corresponding faces of the teeth of the other clutch member and lock the denominational stop device in the position to which it has been turned. By means of the action of this clutch or lock on 90 the shaft 83 and on the key lever 101-102 through the crank arm 94 and link 95 the front end of the denominational key lever is held in its elevated position when the key 109 of the actuating device is depressed as 95 above described. With the downward movement of the rod 110 the key lever 48 acting through the lever 43 and rod 38 turns the column stops to their operative positions and at the same time automatically releases the 100 carriage from the control of the escapement through an actuation of the lever 54-55. Thereupon the carriage is drawn to the left by the spring drum 31 until the denominational stop-facet which is in alignment with 105 the lugs 62 of the column stops is brought into contact with the lug of the first column stop and the denominational stop device is forced to the right and against the lug 85 of the bracket 86, the carriage being arrested 110 when the eye 64 of the denominational stop device strikes the lug 85 of the bracket. The key 109 of the actuating device is then released, whereupon the feed rack of the carriage is re-connected with the feed pinion 19 115 and the column stops 36 are restored to their normal positions by the action of gravity and the restoring springs 18 and 41, the rod 110 and the actuating device 103 being restored 120 to their normal positions by the spring 112. 125 130

The clutch member 91 is forced out of engagement with the other clutch member as the denominational stop device is moved back to the lug 85 by the action on it of the column stop as above described, and so long as the key 109 of the actuating device is held depressed, the lug 62 of the column stop, then extending over the denominational stop device, as represented in Fig. 8, prevents this device from turning, but when the key 109 is released the denominational stop device is turned back to its proper position by the upward action of the spring 98 on the block 96 affixed to the rod 95. While the denominational stop device is being thus moved by the spring 98, the spring 92 is prevented from forcing this device to the left along the shaft 83, by the action on the lug 62 of one of the ribs above described, or of that part of the head 65 which forms the right side of the groove 81' and which is practically a rib. The rib whose face is in the plane of the denominational stop-facet with which the column stop co-acted bears against the right side of the lug 62 as the denominational stop device is turned backward, until the shaft 83 is restored to its normal position. The lower ends of the ribs on the denominational stop device then pass out of alignment with the lug 62 of the engaged column stop and the denominational stop device is forced to the left by the spring 92 and the members of the clutch are reengaged with each other.

It will be observed that when the parts of the tabulating mechanism described are in their normal positions the carriage may be advanced step-by-step under the control of the common feed mechanism or may be moved back and forth by hand without interference from the tabulator stops, the stop device mounted on the shaft 83 then being movable by the carriage along that shaft without being subject to contact with any of the column stops.

The invention may be embodied in forms differing in various respects from the particular form shown and specifically described herein.

What I claim as new and desire to secure by Letters Patent, is:—

1. In tabulating mechanism of a typewriting machine, the combination with the carriage of two stops co-operative with each other to arrest the carriage, and means operative by hand to move both of said stops while the carriage is at rest, said means including a lever pivoted on a fixed axis and connected with one of said stops, and a pivoted actuating device operative on said lever when said device is moved on its pivotal axis, and said device being movable on its pivotal axis when said lever is at rest and being operative to actuate said other stop.

2. In tabulating mechanism of a typewriting machine, the combination with the

carriage of two stops co-operative with each other to arrest the carriage, and means operative by hand to move both of said stops while the carriage is at rest, said means including a lever and an actuating device pivoted together, the lever being connected with one of said stops, and the actuating device being operative to impart motion to said lever and the stop connected therewith, and being movable angularly to actuate said other stop.

3. In tabulating mechanism of a typewriting machine, the combination with the carriage of two stops co-operative with each other to arrest the carriage, and means operative by hand to move both of said stops while the carriage is at rest, said means including a lever and an actuating device mounted on a common fixed axis, the lever being connected with one of said stops, and the actuating device being operative to impart motion to said lever and the stop connected therewith, and being movable angularly to actuate said other stop.

4. In tabulating mechanism of a typewriting machine, the combination with the carriage of two stops co-operative with each other to arrest the carriage, and means operative by hand to move both of said stops while the carriage is at rest, said means including an actuating device pivoted at one end to a support and movable at its other end in one direction to actuate one of said stops, and in the opposite direction to actuate the other stop.

5. In tabulating mechanism of a typewriting machine, the combination with the carriage of two stops co-operative with each other to arrest the carriage, and means operative by hand to move both of said stops while the carriage is at rest, said means including an actuating device pivoted at one end to a support on the frame of the machine and extending thence forward beyond the front posts of the frame, said device being movable at its front end upward and downward and being operative when it is so moved to actuate both of said stops.

6. In tabulating mechanism of a typewriting machine, the combination with the carriage and carriage release mechanism of two stops co-operative with each other to arrest the carriage, and means operative by hand to move one of said stops and to actuate the carriage release mechanism while the carriage is at rest, said means including a lever pivotally mounted on the frame of the machine and connected with one of said stops, and a pivoted actuating device operative on said lever when said device is moved on its pivotal axis, and said device being movable on its pivotal axis when the lever is at rest and being operative on the carriage release mechanism.

7. In tabulating mechanism of a typewriting machine, the combination with the

writing machine, the combination with the carriage and carriage release mechanism of two stops coöperative with each other to arrest the carriage, and means operative by hand to move one of said stops and to actuate the carriage release mechanism while the carriage is at rest, said means including a lever and an actuating device pivoted together and mounted on the frame of the machine, the lever being connected with one of said stops, and the actuating device being operative on said lever and being movable on its pivotal axis while the lever is at rest and being operative on the carriage release mechanism.

8. In tabulating mechanism of a type-writing machine, the combination with the carriage and carriage release mechanism of two stops coöperative with each other to arrest the carriage, and means operative by hand to move one of said stops and to actuate the carriage release mechanism while the carriage is at rest, said means including a lever and an actuating device mounted on the frame of the machine and on a common axis, the lever being connected with one of said stops, and the actuating device being movable on said axis while the lever is at rest and being operative on said lever and the carriage release mechanism.

9. In tabulating mechanism of a type-writing machine, the combination with the carriage and carriage release mechanism of two stops coöperative with each other to arrest the carriage, and means operative by hand to move one of said stops and actuate the carriage release mechanism while the carriage is at rest, said means including a pivoted actuating device whose pivotal axis is at one end thereof and which has a finger piece at its other end, and said actuating device being movable in one direction on said pivotal axis to actuate one of said stops, and in the opposite direction on said pivotal axis to actuate the carriage release mechanism.

10. In tabulating mechanism of a type-writing machine, the combination with the carriage and carriage release mechanism of two stops coöperative with each other to arrest the carriage, and means operative by hand to move one of said stops and actuate the carriage release mechanism while the carriage is at rest, said means including a pivoted actuating device whose pivotal axis is at one end thereof and which extends thence forward beyond the front posts of the frame, said device having a finger piece at its front end and being movable in opposite directions on said pivotal axis and being operative with one movement to actuate one of said stops and with the other movement to actuate the carriage release mechanism.

65 11. In tabulating mechanism of a type-

writing machine, the combination with the carriage and carriage release mechanism of two stops coöperative with each other to arrest the carriage, and means operative by hand to move both of said stops and to actuate the carriage release mechanism while the carriage is at rest, said means including a lever and an actuating device, each pivoted on a fixed axis and said lever being connected with one of said stops, the actuating device being operative to impart motion to said lever and the stop connected therewith, and being movable angularly to actuate said other stop and the carriage release mechanism.

12. In tabulating mechanism of a type-writing machine, the combination with the carriage and carriage release mechanism of two stops coöperative with each other to arrest the carriage, and means operative by hand to move both of said stops and to actuate the carriage release mechanism while the carriage is at rest, said means including a lever and an actuating device pivoted together, the lever being connected with one of said stops, and the actuating device being operative to impart motion to said lever and the stop connected therewith and being movable angularly to actuate said other stop and the carriage release mechanism.

13. In tabulating mechanism of a type-writing machine, the combination with the carriage and carriage release mechanism of two stops coöperative with each other to arrest the carriage, and means operative by hand to move both of said stops and to actuate the carriage release mechanism while the carriage is at rest, said means including a lever and an actuating device mounted on a common fixed axis, the lever being connected with one of said stops and the actuating device being operative to impart motion to said lever and the stop connected therewith, and being movable angularly to actuate said other stop and the carriage release mechanism.

14. In tabulating mechanism of a type-writing machine, the combination with the carriage and carriage release mechanism of two stops coöperative with each other to arrest the carriage, and means operative by hand to move both of said stops and to actuate the carriage release mechanism while the carriage is at rest, said means including an actuating device pivoted at one end to a support and movable at its other end in one direction to actuate one of said stops and in the opposite direction to actuate the other stop and the carriage release mechanism.

15. In tabulating mechanism of a type-writing machine, the combination with the carriage and carriage release mechanism of two stops coöperative with each other to arrest the carriage, and means operative by hand to move both of said stops and to actuate the carriage release mechanism while

- the carriage is at rest, said means including an actuating device pivoted at one end to a support on the frame of the machine and extending thence forward beyond the front posts of the frame, said device being movable at its front end upward and downward and being operative when it is so moved to actuate both of said stops and the carriage release mechanism.
- 10 16. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means to keep said device in the proper position as the carriage travels, and a stop coöperative with each of said denominational stop-facets to arrest the carriage.
- 15 17. In tabulating mechanism of a type-writing machine, the combination with the carriage of a shaft, a device engaged with said shaft and movable by the carriage back and forth along said shaft, said device having on it a series of denominational stop-facets, a key connected with said shaft and operative thereon to turn said device to as many positions as there are denominational stop-facets on said device, automatic locking means to keep said stop from turning as the carriage travels, and a stop coöperative with each of said denominational stop-facets to arrest the carriage.
- 20 18. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means, comprising ratchet teeth and a spring, operative to keep said device in the proper position as the carriage travels, and a stop coöperative with each of said denominational stop-facets to arrest the carriage.
- 25 19. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising ratchet teeth and a spring, operative to keep said device from turning as the carriage travels, and a stop coöperative with each of said denominational stop-facets to arrest the carriage.
- 30 20. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts, operative to keep said device from turning as the carriage travels, the spring being on said shaft and one of said parts being attached to the carriage and the other to said device, and a stop coöperative with each of said denominational stop-facets to arrest the carriage.
- 35 21. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts having co-acting ratchet teeth thereon, the spring being on said shaft and one of said parts being fast on the carriage and the other on said device, and a stop coöperative with each of said denominational stop-facets to arrest the carriage.
- 40 22. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means to keep said device in the proper position as the carriage travels, and a stop coöperative with each of said denominational stop-facets to arrest the carriage and to unlock said device.
- 45 23. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means to keep said device from turning as the carriage travels, and a stop coöperative with each of said denominational stop-facets to arrest the carriage and to unlock said device.

24. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means, comprising ratchet teeth and a spring, operative to keep said device in the proper position as the carriage travels, and a stop co-operative with each of said denominational stop-facets to arrest the carriage and to unlock said device.
25. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising ratchet teeth and a spring, operative to keep said device from turning as the carriage travels, and a stop co-operative with each of said denominational stop-facets to arrest the carriage and to unlock said device.
26. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts, operative to keep said device from turning as the carriage travels, the spring being on said shaft and one of said parts being attached to the carriage and the other to said device, and a stop co-operative with each of said denominational stop-facets to arrest the carriage and to disengage said interlocking parts.
27. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts having co-acting ratchet teeth thereon, the spring being on said shaft and one of said parts being fast on the carriage and the other on said device, and a stop co-operative with each of said denominational stop-facets to arrest the carriage and to disengage said interlocking parts.
28. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means to keep said device in the proper position as the carriage travels, a stop co-operative with each of said denominational stop-facets to arrest the carriage and to unlock said device, and means co-operative with said stop to render said locking means inoperative on said device during its return movement.
29. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means to keep said device from turning as the carriage travels, a stop co-operative with each of said denominational stop-facets to arrest the carriage and to unlock said device, and means co-operative with said stop to render said locking means inoperative on said device during its return movement.
30. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means, comprising ratchet teeth and a spring, operative to keep said device in the proper position as the carriage travels, a stop co-operative with each of said denominational stop-facets to arrest the carriage and to unlock said device, and means co-operative with said stop to render said locking means inoperative on said device during its return movement.
31. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising ratchet teeth and a spring, operative to keep said device from turning as the carriage travels, a stop co-operative with each of said denominational stop-facets to arrest the carriage and to unlock said device, and means co-operative with said stop to render said locking means inoperative on said device during its return movement.

travels, a stop coöperative with each of said denominational stop-facets to arrest the carriage and to unlock said device, and means coöperative with said stop to render said locking means inoperative on said device during its return movement:

32. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts, operative to keep said device from turning as the carriage travels, the spring being on said shaft and one of said parts being attached to the carriage and the other to said device, a stop coöperative with each of said denominational stop-facets to arrest the carriage and to disengage said interlocking parts, and means coöperative with said stop to render said locking means inoperative on said device during its return movement.

33. In tabulating mechanism of a type-writing machine, the combination with the carriage of a device movable back and forth by the carriage, said device having on it a series of denominational stop-facets, key actuated means operative to move said device to as many positions as there are denominational stop-facets on said device, automatic locking means to keep said device in the proper position as the carriage travels, a stop coöperative with each of said denominational stop-facets to arrest the carriage and to unlock said device, and a series of ribs formed on said device and coöperative with said stop to render said locking means inoperative on said device during its return movement.

34. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means to keep said device from turning as the carriage travels, a stop coöperative with each of said denominational stop-facets to arrest the carriage and to unlock said device, and a series of ribs formed on said device and coöperative with said stop to render said locking means inoperative on said device during its return movement.

35. In tabulating mechanism of a type-writing machine, the combination with the carriage of a device movable back and forth

by the carriage, said device having on it a series of denominational stop-facets, key actuated means operative to move said device to as many positions as there are denominational stop-facets on said device, automatic locking means, comprising ratchet teeth and a spring, operative to keep said device in the proper position as the carriage travels, a stop coöperative with each of said denominational stop-facets to arrest the carriage and to unlock said device, and a series of ribs formed on said device and coöperative with said stop to render said locking means inoperative on said device during its return movement.

36. In tabulating mechanism of a type-writing machine, the combination with the carriage of a shaft, a device engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising ratchet teeth and a spring, operative to keep said device from turning as the carriage travels, a stop coöperative with each of said denominational stop-facets to arrest the carriage and to unlock said device, and a series of ribs formed on said device and coöperative with said stop to render said locking means inoperative on said device during its return movement.

37. In tabulating mechanism of a type-writing machine, the combination with the carriage of a shaft, a device mounted on and engaged with said shaft and movable by the carriage back and forth along said shaft, said device having on it a series of denominational stop-facets, key actuated means operative on said shaft to turn said device to as many positions as there are denominational stop-facets on said device, automatic locking means, comprising a spring and interlocking parts, operative to keep said device from turning as the carriage travels, the spring being on said shaft and one of said parts being attached to the carriage and the other to said device, a stop coöperative with each of said denominational stop-facets to arrest the carriage and to disengage said interlocking parts, and a series of ribs formed on said device and coöperative with said stop to render said locking means inoperative on said device during its return movement.

Signed at the borough of Manhattan, city of New York, in the county of New York, and State of New York, this 25th day of June A. D. 1906.
